(57) **CLAIM**

The ornamental design for a motorcycle taillight, as shown and described.

DESCRIPTION

FIG. 1 is a perspective view of the motorcycle taillight. FIG. 2 is a front elevational view of the motorcycle taillight. FIG. 3 is a side elevational view of the motorcycle taillight with the opposite side being a mirror image of the same. FIG. 4 is a top plan view of the motorcycle taillight. FIG. 5 is a perspective view of another embodiment of the motorcycle taillight.

FIG. 6 is a front elevational view of the motorcycle taillight shown in FIG. 5.

FIG. 7 is a side elevational view of the motorcycle taillight shown in FIG. 5 with the opposite side being a mirror image of the same; and,

FIG. 8 is a top plan view of the motorcycle taillight shown in FIG. 5.

The bottom forms no part of the claimed design.

The broken lines form no part of the claimed design.
